United States Patent

Des. 240,680
Patented July 27, 1976

240,680

SEAT OR SIMILAR ARTICLE

Stanley P. Nash, Rte. 1, Riverhill Drive,
Johnson Creek, Wis. 53038

Filed Aug. 30, 1973, Ser. No. 392,854

Term of patent 3½ years

Int. Cl. D6—01

U.S. Cl. D6—62

FIG. 1

FIG.4

FIG. 1 is a front perspective view of a seat showing my design in the form of a sofa;

FIG. 2 is a rear elevational view thereof;

FIG. 3 is a front perspective view of the design shown in the form of a loveseat; and

FIG. 4 is a front perspective view thereof in the form of an armchair.

I claim:

The ornamental design for a seat or similar article, as shown.
